UNITED STATES PATENT OFFICE.

OSCAR ALSPAUGH, OF KINSLEY, KANSAS.

OIL-BURNER.

1,056,142.

Specification of Letters Patent.

Patented Mar. 18, 1913.

Application filed March 6, 1912. Serial No. 681,882.

To all whom it may concern:

Be it known that I, OSCAR ALSPAUGH, a citizen of the United States, residing at Kinsley, in the county of Edwards and State 5 of Kansas, have invented certain new and useful Improvements in Oil-Burners, of which the following is a specification.

This invention relates to improvements in oil burners and is especially adapted to 10 the use of oil-fuel in the fire-pots of stoves, ranges, furnaces and steam boilers.

The particular object of this invention is to improve the combustion of the gas that issues from the burner, by providing an 15 air inlet that is concentric with the burner and deflected upon the gas jets.

A further object is to provide a burner having an air-inlet therethrough, thereby avoiding the usual form of construction 20 wherein the air supply pipe is positioned to one side of the burner and obstructing the flame at that side.

With the above and other objects in view, the present invention consists in the combination and arrangement of the parts as 25 will be more fully described hereinafter, shown in the accompanying drawings, and particularly pointed out in the appended claims it being understood, that changes 30 in form, proportion, size and minor details, may be made within the scope of the claims without departing from the spirit or sacrificing any of the advantages of the invention.

These objects are attained by the means 35 illustrated in the accompanying drawing, in which—

Figure 1 is a vertical sectional view of the burner within the fire-pot of a stove. Fig. 2 is a plan view of air deflector sup- 40 port. Fig. 3 is a bottom plan view of the gas distributing ring, and Fig. 4 is a horizontal sectional view on the line 4—4 of Fig. 1.

Similar reference numerals in all of the 45 figures of the drawing designate like parts.

As shown in the drawing, the device embodies a base plate 5, preferably having a turned-up edge 6, which forms a shallow receptacle or basin. Said base is provided 50 with a tubular extension 7 whose aperture is extended through the base, and a shorter extension 8 arranged concentric and outside of the extension 7, forming a narrow annular chamber 9. Adapted to closely fit

around the extension 7 and be supported by 55 the extension 8, is a gas-jet ring 10, having a conical upper surface 11 and shallow radial grooves 12 formed on its under side.

With the construction thus far described, together with the oil inlet pipe 13 which 60 preferably enters the stove below the burner and connects with the annular chamber 9, is provided a burner that will generate gas that will issue from beneath the gas ring 10, and if ignited, will burn with a steady 65 flame, but to cause the flame to spread to the walls of the fire pot, the following described air-deflector is provided.

Upon the top edge of the extension 7 is supported a spider ring 14 having a central 70 post or support 15 provided with an extension 16 of smaller diameter than the post, forming a shoulder 17. A concave air deflector 18 provided with a central aperture 19 is supported upon the shoulder 17. The 75 bottom edge of the depending wall 20 of this air-deflector preferably extends below the plane of the top edge of the extension 7, thereby forming an annular passageway 21 between said depending wall and said 80 extension 7.

The operation of the device is as follows: Initially oil is fed through the pipe 13 to the chamber 9 and ignited at the point of contact of the ring 10 and the extension 8. 85 As the walls become heated, the oil in the narrow chamber 9 is generated into gas which issues through the grooves 12 of the ring 10. The air passing upward through the extension 7 is heated in its passage, 90 passes through the spider 14 and contacts with the top wall of the deflector 18 and is deflected downward by the depending wall 20. As the air passes downward it strikes the conical or inclined upper surface of the 95 ring 11, uniting with the gas issuing from the burner, and with a tendency of spreading toward the walls of the fire pot. Thus is formed a burner that is highly efficient,

simple in construction, cheap to manufacture, and in which the oil and liquid fuel can be quickly generated into a vapor. The force of the air discharge upon the issuing gas, can be regulated by adjusting the deflector 18 upon the extension 16, thereby 100 raising the lower edge of said deflector and widening the space between the gas jets and said lower edge. Should oil at any time 105

overflow the generating chamber it will be caught by the dished base.

Having thus fully described the invention, what is claimed is:

- 5 1. A burner, comprising a base, two integral extensions projecting upwardly from said base forming a generating chamber therebetween, one of said extensions extending higher than the other, and a burner-ring provided with radial grooves adapted to fit over and around one of said extensions and be supported by the other extension.
- 10 2. A burner, comprising a base, extensions having an air passage therethrough and projecting from said base forming a generating chamber therebetween, a burner ring having a conical upper side supported at the top of said generating chamber, and an air deflector having a depending pe-
- 15

ripheral wall supported upon one of said extensions.

3. A burner, comprising a base, extensions having an air passage therethrough and projecting from said base forming a generator chamber therebetween, one of said extensions extending higher than the other, a burner ring supported at the top of said generating chamber on one of said extensions, a spider ring supported upon the other extension, and an air deflector supported upon said spider ring.

In testimony whereof I affix my signature in presence of two witnesses.

OSCAR ALSPAUGH
